CARTON CONSTRUCTION

Harrison C. Bloomer, Newark, N. Y., assignor to
 Bloomer Bros. Company, Newark, N. Y., a cor-
 poration of New York

Application March 23, 1936, Serial No. 70,295

11 Claims. (Cl. 229—51)

This invention relates to cartons, and particularly to cartons of the tear-apart or pull-apart type.

When various products, such, for example, as ice cream, are packed in cartons, it is often desirable to be able to disassemble the carton in such a manner that it may be laid out flat to obtain free access to the contents so that ice cream, for example, can be removed readily from the carton in the form of a single brick or lump, instead of having to be dug out of the carton bit by bit. Accordingly, it has been proposed to provide cartons in which one of the adhesive joints may be broken by the application of reasonable force, to enable the carton to be opened out flat, a tab is usually provided which may be grasped and pulled to break the joint.

One disadvantage of this construction is that frequently the force exerted upon the tab to open the carton is apt to tear the tab portion from the rest of the carton body, or to tear the body back in a strip having a width equal to the width of the tab portion, instead of breaking the whole adhesive joint and separating the overlapped layers of sheet material from each other as should be done. Such tearing is especially apt to occur where the carton is made of paper or fiber board having a grain running in the same direction as the direction of pull on the tab.

Another disadvantage is that, even when the tab does not tear off or tear back, the breaking of the adhesive joint is apt to cause surface tearing of the sheet material in an objectionable manner.

An object of the present invention is to remedy both of these objections, and particularly to provide a carton so designed and constructed that the tab will not tear off, or tear back when a force is applied to the tab to open the carton, and that no objectionable surface tearing of the sheet material will take place.

Another object is the provision of an improved carton in which surface tearing of the sheet material, when the carton is opened, is confined to the inner or under layer of the two overlapping layers of sheet material, and in which the possible extent of such tearing is limited by an edge of the sheet material closely adjacent the adhesive zone where the tearing begins.

To these and other ends the invention resides in certain improvements and combinations of parts, all as will be hereinafter more fully described, the novel features being pointed out in the claims at the end of the specification.

In the drawings:

Fig. 1 is a view of a carton constructed in ac-

cordance with one embodiment of the invention, seen at a preliminary stage of its manufacture;

Fig. 2 is a view of the same carton completed in knocked-down form;

Fig. 3 is a section substantially on the line 3—3 of Fig. 2;

Fig. 4 is a view similar to Fig. 1 showing a modified form of construction;

Fig. 5 is a view similar to Fig. 2 showing the same modified form of construction in the completed knocked down condition;

Fig. 6 is a view similar to a fragment of Figs. 1 and 4 illustrating a further modification;

Fig. 7 is a view similar to Fig. 6 illustrating still another modification;

Fig. 8 is a similar view illustrating another possible modification of the invention;

Fig. 9 is a section substantially on the line 9—9 of Fig. 8, and

Fig. 10 is a view similar to Figs. 6, 7, and 8 illustrating a further modification.

The same reference numerals throughout the several views indicate the same parts.

The present invention is independent of the exact form or shape of the carton. As a convenient example, there is illustrated in the drawings a carton having panels 11, 12, 13, and 14, and a flap 15, all made from the same strip or piece of paper or fiber board, the panel 11 being shown folded over the panel 12 in the drawings. When the flap 15 is overlapped with the upper edge of the panel 11 and secured thereto, as by adhesive, the panels 11, 12, 13, and 14 then form the four sides of the carton and may be erected into a rectangular cross-section, and the ends of the carton may be closed by suitable end flaps of known construction.

At 16 there is indicated a tab, placed at any convenient point along the edge of the flap 15, to be grasped and pulled upwardly or outwardly to separate the overlying flap layer 15 from the underlying panel layer 11, in order to tear the carton open along this joint and thus obtain easier access to the contents of the carton.

The layers 11 and 15 may be secured to each other by a zone or line of adhesive 17. In Fig. 1, this zone or line of adhesive is shown as a continuous strip of adhesive extending throughout the length of the flap 15, but it is not necessarily in this form. The adhesive may be of any suitable kind, such as animal or vegetable glue, casein glue, or other known forms of adhesive commonly used in the carton art. When the surface of the panel 11 with which the adhesive comes into contact is a surface having a paraffine

coating, it is preferred to use a glue having a paraffine solvent in it, commonly known in the trade as a paraffine glue. Such a glue will penetrate the paraffine and make a bond with the fibrous material beneath. When no paraffine coating is used on that part of the panel 11 with which the adhesive comes into contact, it is preferred to use an adhesive of the kind known in the trade as a flexible glue, as distinguished 10 from a hard glue or glue which will crystallize. The adhesive is usually applied by the carton-making machinery to the under surface of the flap 16, as shown in Fig. 1, and then when the blank is folded over from the position shown in 15 Fig. 1 to the position shown in Fig. 2, this zone or line of adhesive will come down onto the upper surface of the panel 11 near the top edge thereof, and secure the parts 11 and 16 to each other.

If the flap 16 be secured to the panel 11 with 20 a uniform degree of intensity of adhesion throughout the entire length of the adhesive zone, then a pull on the tab 16 in a direction crosswise of this adhesive zone is very apt to cause the flap 16 to tear along lines extending inwardly (vertically when viewed as in Figs. 1 and 2) at approximately the side edges or corners of the tab 16. This is particularly true when the grain of the carton board runs vertically or around the periphery of the carton. 25 Such tearing inwardly at the sides of the tab appears to be due to the fact that when the tab is pulled, there is initially a greater intensity of stress produced in the flap 16 at the sides of the tab, than at the other points along the flap 16 30 more remote from the tab.

To avoid such tearing, it is desirable to reduce the intensity of the adhesive connection or bond between the layers 11 and 16 at points adjacent the sides or corners of the tab 16. When the 40 adhesive bond at these points is thus reduced, the resistance to the pulling back of the tab is lessened at these points where the greatest stress occurs so that tears are not likely to start at these points. At other points, where the intensity 45 of the adhesive connection is not thus reduced, the intensity or concentration of the stress is less, so that there is little or no danger of tearing.

In order thus to reduce the intensity or 50 strength of the adhesive bond at the desired points, one or the other of the two overlapped layers of sheet material is preferably provided with a coating to weaken the adhesive bond. This may be accomplished by the use of a coating 55 of material which has a less affinity for the adhesive than the carton material. Or, if it is desired for any reason to coat the carton material throughout substantially the entire area of the adhesive with a material having a reduced 60 affinity for adhesive, then a thicker or heavier coating of the same material or a coating of a different affinity-reducing material is employed at the desired points (near the sides of the tab 16) to produce the effect above mentioned.

65 So far as the prevention of tearing inwardly from the sides or corners of the tab is concerned, the affinity-reducing or bond-weakening coating may be applied either to the layer 11 or to the layer 16. It is preferred, however, to apply this 70 coating to the layer 11, and to arrange it in such a way that it not only serves to prevent tearing at the tab corners, but also assists in confining surface tearing of the sheet material to the layer 11, reducing or eliminating surface tearing 75 of the layer 16.

In the embodiment here shown, the bond-weakening or affinity-reducing coating is applied to the outer surface of the inner layer 11 in the form of a strip 18 having relatively narrow portions throughout the major part of its length 5 overlapping a small part only of the width of the adhesive zone 17, and having enlargements or wider portions 19 adjacent the sides or corners of the tab 16, which wider portions 19 extend throughout substantially the entire width of the 10 adhesive zone 17 when the parts are in the completed position shown in Fig. 2. This coating 18 thus reduces the adhesive bond to some slight extent throughout substantially the entire length 15 of the adhesive zone, but reduces it especially and to a greater extent at points approximately opposite the sides or corners of the tab 16, where the greatest stress occurs in pulling the tab to open the carton, and where the greatest likelihood 20 of tearing occurs.

Since the coating 18 extends throughout substantially the entire length of the adhesive zone 17 at the outer edge of such zone (that is, at the lower edge when viewed as in Fig. 2, or the edge closest to the extreme edge of the flap 16) it follows that as the flap 16 is pulled upwardly away from the panel 11, the adhesive 17 at its lower edge where the stress comes first, will tend to pull away from the coating 18 and remain on the flap 16, instead of pulling away from the 30 flap 16 and remaining on the coating 18. This pulling away from the coating 18 and remaining on the flap 16 is highly desirable, because it eliminates any surface tearing of the fibrous material of the layer 16. As pulling is continued, 35 the body of adhesive 17 will tend to remain firmly attached to the flap 16, producing no surface tearing of this flap, and will tend to break away from the layer 11 as the breaking of the joint proceeds past the edge of the coating 18. 40 Thus such surface tearing of the fibers as is produced will be produced in the layer 11 rather than in the layer 16 and will be confined to the relatively narrow area between the coating 18 and the extreme end or edge of the layer 11, 45 since the tearing will necessarily stop when the extreme edge of the sheet is reached.

The coating 18 may be of any suitable material which has the desired lessened affinity for the particular glue or other adhesive which is used. 50 A layer of paraffin has been found quite satisfactory in many instances for forming the coating 18. It is preferred, however, to use an ink of a type which tends to repel the adhesive and has a relatively small affinity for the adhesive. 55 Satisfactory inks for this purpose are printing or lithographing inks with a base of oil or wax, or a combination of oil and wax. Printing or lithographing inks with an aniline base are also satisfactory in some instances. The coating 18 60 when in the form of ink, can be applied very quickly to the carton wall 11 by a simple printing operation.

A modified form of construction is illustrated in Figs. 4 and 5. Here, the main difference is 65 that the adhesive, instead of being applied in the form of a continuous strip 17, is applied in the form of a discontinuous line or zone of adhesive, such as a series of spaced spots 25. The diamond-shaped spots here illustrated are particularly efficient, because the lower points of the diamonds present only a slight resistance at the beginning of the pulling apart or separating 70 operation, which resistance increases as the pulling proceeds. Thus it is easy to start the separating 75 operation.

ration or breaking of the joint by a slight force, and once the breaking is started, it continues easily with the continuous application of reasonable force.

5 Except for the use of a zone or line of spaced spots of adhesive in place of a continuous strip of adhesive, the construction shown in Figs. 4 and 5 may otherwise be identical with the construction illustrated in Figs. 1 to 3, and the same parts 10 are indicated by the same reference numerals.

If desired, the affinity-reducing or bond-weakening coating may comprise two or more layers of the same or different material, superimposed upon each other. For instance, the 15 modification illustrated in Fig. 6 comprises a coating 28 of the same shape previously disclosed in connection with the coating 18, and having a wider portion 29 corresponding to the wider portion 19 previously disclosed. This coating may 20 be of adhesive repelling ink as above mentioned. The carton is also provided with an overlapping coating 30, of the same material, and of a width sufficient to cover the entire width of the adhesive zone. Either of these two coatings may be applied first. With this arrangement, the bond between the adhesive and the fibrous layer to which the coatings are applied will be weakened to some extent throughout the entire area of the adhesive (thus confining surface tearing of the sheet material to this layer rather than to the other layer of sheet material), and will be weakened to an even greater extent where the bond-reducing coating is of double thickness, at the portions 28 and 29 (thus preventing tearing back at the sides 35 or corners of the tab 16).

This arrangement of using two superimposed layers of adhesive-repelling or bond-reducing material is not confined, of course, to the use of ink as the bond-reducing material. Fig. 7 is intended 40 to illustrate a similar arrangement in which both layers are of paraffin, one coating at 38 with the enlargement 39 corresponding in shape to the previously described coatings 18, 19, 28, and 29, and the other coating being indicated at 40. Throughout the area of the coating 38, 39, the 45 paraffin will be of double thickness, and the adhesive bond will be greatly reduced in the manner previously explained in connection with Fig. 6. Where the adhesive comes in contact only with the coating 40 and not with the coating 38, 39, the 50 bond will also be reduced but to a lesser extent, and this reduction of the bond will be sufficient to confine surface tearing of the sheet material to the layer to which these coatings are applied 55 (preferably the layer 11), preventing such surface tearing from occurring in the other layer.

Another modification is illustrated in Fig. 8. Here there is provided a coating 48, with an enlargement 49, corresponding in shape and arrangement to the coatings 18 and 19 previously described, this coating 48, 49 being of ink. A coating 50 of paraffin is also employed, in the manner above mentioned in connection with the coatings 30 and 40. It is immaterial whether the paraffin coating or the ink coating be applied first, but it is usually desirable to apply the ink first and then the paraffin, as shown in Fig. 9. Since both the paraffin and the ink have the effect of repelling the adhesive or reducing the adhesive bond, it follows that throughout the area of the ink coating, where both the paraffin and the ink are present, the bond will be greatly reduced, and outside of the area of the ink 70 coating, where only the paraffin coating is pres-

ent, the adhesive bond will also be reduced, but to a lesser extent.

In the modification illustrated in Fig. 10, a bond-reducing coating (which may be either of ink, or of paraffin, or of any other suitable material having the desired effect) is employed in a somewhat different form or shape. Here, the coating is in the form of two or more narrow strips or lines 55. Between these strips or lines, the adhesive will contact with the sheet material 10 of which the carton is made and have its full adhesive power or bond, but along these coating lines 55 the bond will be reduced enough so that the adhesive will tend to remain attached to the other layer of sheet material and tend to break 15 away from this layer to which the coatings 55 are attached. Surface tearing of the material is thus confined to this coated layer, where the tearing can proceed no further than the closely adjacent edge of the material, and tearing is 20 avoided in the flap 15, where such surface tearing could proceed an indefinite distance, into the panel 14 or perhaps even further.

While certain embodiments of the invention have been disclosed, it is to be understood that 25 the inventive idea may be carried out in a number of ways. This application is, therefore, not to be limited to the precise details described, but is intended to cover all variations 30 and modifications thereof falling within the spirit of the invention or the scope of the appended claims.

I claim:

1. A carton comprising two overlapping layers 35 of fibrous sheet material, adhesive means connecting said two layers to each other, one of said layers being adapted to be pulled away from the other layer to break the adhesive connection between them by a pull exerted on said one of said layers adjacent said adhesive means, said one of said layers during such pulling being subjected, in a portion adjacent the point where the pulling force is applied, to stress of high intensity relatively to the stress produced in other portions of said one layer, and means for reducing the strength of the adhesive bond between 40 said two layers at said portion of relatively high stress.

2. A carton comprising two overlapping layers 50 of fibrous sheet material, adhesive means connecting said two layers to each other, one of said layers being adapted to be pulled away from the other layer to break the adhesive connection between them by a pull exerted on said one of said layers adjacent said adhesive means, said one of said layers during such pulling being subjected, in a portion adjacent the point where the pulling force is applied, to stress of high intensity relatively to the stress produced in other portions 55 of said one layer, and means for rendering the adhesive bond between said two layers weaker at said portion of relatively high stress than at other portions of said layers.

3. A carton comprising two overlapping layers 65 of fibrous sheet material, adhesive means for connecting said two layers to each other substantially along a zone, tab means on one of said layers to be grasped to pull said layer away from the other of said layers to break the adhesive connection between them, and means for reducing the intensity of said adhesive connection adjacent said tab means.

4. A carton comprising two overlapping layers 70 of fibrous sheet material, adhesive means for connecting said two layers to each other substantial- 75

ly along a zone, tab means on one of said layers to be grasped to pull said layer away from the other of said layers to break the adhesive connection between them, said one of said layers being subjected, during the pulling operation, to stress of relatively high intensity adjacent one side of said tab means, and means for reducing the intensity of the adhesive connection between said two layers at a point on said zone approximately in line with said side of said tab means.

5. A carton comprising two overlapping layers of fibrous sheet material, a zone of adhesive connecting said two layers to each other, one of said layers having a portion which may be conveniently grasped to pull said one of said layers away from the other of said layers to break the adhesive connection, and a coating on one of said layers having less affinity for said adhesive than said sheet material, said coating extending across 10 a greater part of said zone of adhesive at a point adjacent said means to be grasped than at other points of said zone.

6. A carton comprising an inner layer and an outer layer of fibrous sheet material overlapped 15 with each other, a zone of adhesive connecting said two layers to each other, tab means on said outer layer to be conveniently grasped to pull said outer layer away from said inner layer to break the adhesive connection between them, and a 20 coating of material on the outer surface of said inner layer to reduce the affinity of the coated portion of said inner layer for said adhesive, said coating extending along said zone of adhesive through a part only of the width thereof through- 25 out most of the length of said zone, and extending through a greater width of said zone at points adjacent said tab means.

7. A carton comprising an inner layer and an outer layer of fibrous sheet material overlapped 30 with each other, tab means on said outer layer to be grasped to pull said layers apart, a zone of adhesive applied to the inner surface of the outer layer for contact with the outer surface of the inner layer to secure said two layers to each other, 35 and a coating on the outer surface of the inner layer of material reducing the adhesion between said adhesive and said inner layer, said coating extending along said zone of adhesive and having a less width than the full width of said zone throughout the major portion of the length of 40 said zone, and being substantially wider at points on said zone approximately in alignment with the sides of said tab means, to reduce the adhesive connection between said two layers in line 45 with the sides of said tab means, and to reduce the possibility of said outer layer tearing when force is applied to said tab means.

8. A carton comprising an inner layer and an outer layer of fibrous sheet material overlapped

5 with each other, said outer layer having a portion to be grasped to pull said outer layer away from said inner layer, a series of spaced spots of adhesive connecting said two layers to each other, and a coating of material on the outer surface of the inner layer throughout at least a part of the area of said spots of adhesive, to reduce the strength of the bond between said adhesive and said inner layer below the strength of the bond between said adhesive and said outer layer, so 10 that when said two layers are pulled apart, the adhesive will be more likely to pull away from the inner layer than from the outer layer and so that any surface tearing of the sheet material will occur mainly in the inner layer.

9. A carton comprising an inner layer and an outer layer of fibrous sheet material overlapped with each other, said outer layer having a portion to be grasped to pull said outer layer away from said inner layer, a series of spaced spots of 15 adhesive connecting said two layers to each other, and a coating of adhesive repellent material on the outer surface of the inner layer throughout at least a part of the area of said spots of adhesive, to reduce the strength of the 20 bond between said adhesive and said inner layer below the strength of the bond between said adhesive and said outer layer, so that when said two layers are pulled apart, the adhesive will be more likely to pull away from the inner layer than from the outer layer and so that any surface tearing of the sheet material will occur 25 mainly in the inner layer.

10. A carton comprising two overlapped layers of fibrous sheet material, means on one of said layers to be grasped to pull said one of said layers away from the other of said layers, a zone of spaced spots of adhesive connecting said two layers to each other, and a coating of adhesive repellent material on one of said layers extending 30 along said one of said layers adjacent said zone of adhesive and having a width extending substantially across the full width of said zone of adhesive adjacent the sides of said means to be grasped and having a substantially lesser width 35 along the rest of said zone of adhesive.

11. A carton of the type wherein two overlapping layers of sheet material are adhesively connected to each other and are adapted to be pulled away from each other to break the adhesive connection between them by a pulling force applied to one layer and producing a higher intensity of stress in that layer adjacent the point where the force is applied than at other points more remote therefrom, characterized by means 40 for rendering the adhesive bond between said two layers weaker at said point of high intensity stress than at said other more remote points.

HARRISON C. BLOOMER.
